UNITED STATES PATENT OFFICE

144,501

DESIGN FOR A BADGE OR LIKE ARTICLE

Minnie G. Garrett and Robert B. J. Biggins,
Kansas City, Kans.

Application August 8, 1945, Serial No. 121,321

Term of patent 14 years

(Cl. D29—2)

To all whom it may concern:

Be it known that we, Minnie G. Garrett and Robert B. J. Biggins, citizens of the United States, residing at Kansas City, in the county of Wyandotte and State of Kansas, have invented a new, original, and ornamental Design for a Badge or like article, of which the following is the specification, reference being had to the accompanying drawing, forming part thereof.

Fig. 1 is a side view of a badge or like article showing our new design;

Fig. 2 is an end view thereof.

We claim:

The ornamental design for a badge or like article, substantially as shown.

MINNIE G. GARRETT.
ROBERT B. J. BIGGINS.
